Emil E. Fachon, Edgewood, R. I., assignor to Bulova Watch Company, Inc., New York, N. Y., a corporation of New York

Application November 26, 1948, Serial No. 149,842

Term of patent 7 years

(Cl. D45—4)

To all whom it may concern:

Be it known that I, Emil E. Fachon, a citizen of the United States, residing at 12-A Sefton Drive, Edgewood, county of Providence, and State of Rhode Island, have invented a new, original, and ornamental Design for a Bracelet or Similar Article, of which the following is a specification, reference being had to the accompanying drawing, forming part thereof.

Fig. 1 is a top plan view of a bracelet showing my new design;

Fig. 2 is a side elevational view of the bracelet, and

Fig. 3 is a bottom plan view of a portion thereof;

Fig. 4 is an end elevational view taken on line 4—4 in Fig. 2 and viewed in the direction indicated by the arrows; and

Fig. 5 is a top plan view of the bracelet shown in Fig. 1 with the links in an expanded position.

The links shown in full lines are repeated across the length of the bracelet as indicated by the broken line disclosures in Figs. 1, 2 and 5.

I claim:

The ornamental design for a bracelet or similar article, as shown and described.

EMIL E. FACHON.
